UNITED STATES PATENT OFFICE

2,475,881

TANK LEVER

Basil R. Crampton, Grand Rapids, Mich., assignor, by mesne assignments, to Crampton Manufacturing Company, Grand Rapids, Mich., a corporation of Michigan

Application May 29, 1946, Serial No. 673,001

1 Claim. (Cl. 4—67)

1.

This invention relates to flushing tank levers and is directed to greatly economizing the production of such levers over the way they have been previously made, as disclosed in my earlier Patent No. 2,233,159, issued February 25, 1941.

A flushing tank lever mounted on a flushing tank has exposed at the outer side of the tank the operating handle and an escutcheon which covers the outer end of a spud or tank wall fixture extending through the wall of the tank, and through which the complete lever member is mounted for a limited rocking movement. In my prior patent above identified, the handle part of the lever and such escutcheon are made integral with an enlargement of the handle where it connects to the stem passing through the tank wall fixture, or spud, to obtain such covering of the outer end of the spud. Such handle member of the complete lever is produced as a casting which may be of brass or various other materials, but in present day practice is usually of a die cast metal, the major ingredient of which is zinc. Such handles must have an attractive and decorative finish as the castings made from the die cast metal are subject to some oxidation which gives them a dull coating which progressively increases with age. Therefore, it had been common practice before the second World War, and will be hereafter, to plate said handles with a non-oxidizable plating which involves a nickel plating with a subsequent protective chromium plating thereover. The polishing and buffing and the plating of the handles is one of the major items of expense in such flushing tank lever manufacture.

In the present invention the use of a decorative coating, and particularly plating, required in practice, is done away with. Stainless steel, an alloy of steel and chromium does not lose its luster of appearance through oxidizing, requires no plating and maintains its attractiveness of appearance for the life of the flushing tank lever. Stainless steel however is a very difficult material to process, is expensive and for the attainment of the necessary economy and manufacture of flush tank levers must be used in a very small quantity for each lever.

The present invention has resulted in the production of a flush tank lever in which cost of manufacture in comparison with levers having

handles of a construction disclosed in my prior issued patent is reduced approximately 30%, with a consequent ability to furnish the levers to purchasers and users thereof at a reduced price. The invention which I have produced uses a very small weight of stainless steel with each lever, approximately three and one-half pounds for one hundred levers, so that notwithstanding the relatively high cost of stainless steel the lever produced is greatly decreased in cost of production without detriment to operation or appearance. Furthermore, by novel construction the stainless steel may be used to produce a separate escutcheon and separate handle covering, it being a practical impossibility to work and draw the stainless steel material in one piece in the shape and form required to cover the handle shown in my prior patent.

There is, therefore, involved numerous novel changes in construction in the making of the parts and in the assembly thereof, for the attainment of the desired enumerated ends.

An understanding of the invention may be had from the following description taken in connection with the accompanying drawing, in which,

Fig. 1 is a fragmentary elevation of the upper portion of a flushing tank, having the lever of my invention mounted thereon.

Fig. 2 is a fragmentary enlarged vertical section through the tank and the lever substantially at the plane of the axis of the tank wall fixture or spud.

Fig. 3 is a horizontal section on a plane substantially coincident with said axis of the tank wall fixture.

Fig. 4 is a fragmentary vertical longitudinal section through the outer handle portion of the completed lever, and

Fig. 5 illustrates in perspective, separated from each other, the several parts used in making a flushing tank lever in accordance with my invention.

Like reference characters refer to like parts in the different figures of the drawing.

The flushing tank is of regular construction having an outer vertical wall through which an opening for the passage of the tank wall fixture or spud is made. The opening is generally square in cross section. The spud or fixture has an outer head of circular outline, greater in diam-

eter than the transverse dimension of the opening through the tank, which lies against the outer side of the tank wall 1. The spud is cast from die cast material and from the head 2 a section 3 square in cross section extends and from it an integral exteriorly threaded section 4. At the inner end of the threaded section 4 and at one side thereof a projecting finger 5 extends, the function of which will thereafter be described. The tank wall fixture is hollow having a cylindrical opening therethrough from its outer end nearly to its inner end through which inner end a slot 6 is made in a transverse end portion 1, the slot 6 being disposed substantially on a diameter of the spud and closely adjacent the inner side of the projecting finger 5 (Fig. 5). Such tank wall fixture has the threaded section 4 and the square section 3 inserted into and through the opening in the tank wall until the head 2 comes against the outer side of the wall, and receives a binding nut 8 screwed onto the projecting end of the section 4 which is brought against the inner side of the tank wall, securing the spud in place and against longitudinal or rotative movement.

The movable lever part of the flushing tank lever includes an inside lift arm, a transverse spindle and an outer operating handle. The lift arm and spindle are made from a length of metal in bar stock, the lift arm 9 at one end having the spindle 10 turned at right angles therefrom. Near the free end of the spindle 10 and in one of its edges a notch 11 is provided. The spindle passes through the slot 6, which is wide enough that the spindle may have a limited rocking movement therein, and the adjacent side of the lift arm 9 comes very closely adjacent to the free end of the finger 5 as shown in Fig. 3 in the completed lever. The handle has an inner body, die cast with a substantially solid head 12 at one end from which an open frame extends to a side, having spaced apart sides 13 connected at their outer ends by a transverse integral end 14 as best shown in Fig. 5. At the inner side of the head 12 a projection is cast in several diameters. Immediately adjacent the inner side of the head 12 a short cylindrical section 15 is provided from which a second and longer cylindrical section 16 extends, the diameter of which is slightly less than the diameter of the section 15, and from the inner end of the section 16 a terminal section 17 extends, the exterior diameter of which is such that it is received within the outer end of the cylindrical opening in the hollow spud or tank wall fixture described. A slot 18 divides the projection 17 substantially in two equal parts and said slot extends the full length of the sections 16 and 17 and into the head 12, terminating a short distance from the outer side of the head as best shown in Fig. 2. The width of the bar stock from which the lift arm 9 and the transverse spindle 10 are made is approximately equal to, though perhaps slightly less than the width of the slot from one edge to the other in the section 17, and the edges of the spindle where it enters said slot and is inserted through the cylindrical sections 15, 16, is less than the diameters of the sections 15 and 16 and less than the distance between the opposite sides of the head.

An escutcheon or cover plate 19 substantially in the form of a dome, open at its inner side is pressed from thin stainless steel material, having an opening 20 at what may be termed its "top," the diameter of which is such that the short cylindrical section 15 may pass therethrough; that is, the dome is passed over the inwardly

extending projection at the end of the handle and over the short collar 15 after which the collar is upset and distorted or rolled to provide a continuous retaining rib 21 (Figs. 2 and 3) whereby the escutcheon or cover member 19 is permanently secured to the die cast handle member. The interior diameter of the escutcheon 19 at its open end is greater than the exterior diameter of the head 2 whereby it may reach substantially to the outer side of the tank wall 1 and cover the outer end of the tank wall fixture (Figs. 2 and 3).

In the production the spud is die cast, the handle member described is die cast, and the bar is fabricated to provide the inner lift arm having the spindle with the notch 11 therein. The spindle is inserted at its free end through the opening 6 and projected through the spud and into the slot at 18 until the end of the spindle reaches the bottom of the slot and with the lift arm closely adjacent the free end of the finger. In such assembly of the parts the inner cylindrical projection 17 will be received within the outer end of the spud, then by a punch press operation or equivalent pressure, the metal of the head opposite the notch 11 is forced inwardly into said notch, as shown at 11a in Fig. 2, providing a normally permanent and inseparable connection of the handle member to the outer end of the spindle.

The lever is completed by providing the die cast handle member with a covering of thin stainless steel material. Such covering pressed from a plate of thin metal has an outer side 22 with a continuous flange extending from it at its edges, said flanges having two side sections 23 and two end sections 24 and 25 conforming to and closely embracing the die cast handle member. From the inner edges of the sides 23 integral tabs 26 extend. This covering is placed over the die cast member of the handle and the tabs bent toward each other to come against parts 13 thereby retaining the cover in place.

With a tank lever as described the depression which is made by pressing the metal inwardly into a notch at 11 is covered and the inner edges 45 of the covering for the handle at the rounded end at 25 and adjacent thereto are brought into direct engagement with the outer end or top of the dome escutcheon 19. Therefore all visible exposed portions of the tank lever carry the stainless steel covering which is not subjected to oxidizing or other deterioration in appearance. All plating is dispensed with and the cost of manufacture is reduced, as previously indicated, approximately 30%. The finger 5 serves as a stop against any axial movements of the spud and spindle relative to each other.

The invention is very practical. The construction described is simple, sturdy and particularly 60 economical. The invention is defined in the appended claims and is to be considered comprehensive of all forms of structure coming within their scope.

I claim:

65 In a flushing tank lever, a tank wall fixture adapted to be fixedly secured to and extend through the wall of a flushing tank, a movable lever member having a spindle extending axially through the fixture and at its inner end having a lift arm permanently connected thereto and extending away therefrom and at its outer end having an operating handle permanently connected and extending away therefrom, said handle at its inner end having an inwardly extending cylindrical projection comprising three sec-

tions of progressively decreasing diameters, a dome of thin material having an opening at its outer side through which said projection extends, the opening being of a size to pass the largest diameter section of the projection whereby the projection may be laterally offset to secure the dome in permanent connection with the handle in a position to cover the outer end of said tank wall fixture, and a second covering of the same material secured to said handle whereby all exposed portions of the lever at the outer side of a flushing tank on which mounted are of said material.
